UNITED STATES PATENT OFFICE.

RAYMOND KNABLE, OF CHICAGO, ILLINOIS.

AUTOMATIC COAT-HANGER-FORMING DEVICE.

Application filed February 23, 1926. Serial No. 90,168.

My invention relates to improvements in automatic coat hanger forming devices, and it consists in the combinations, constructions, and arrangements herein described and 5 claimed.

An object of my invention is to provide an automatic garment hanger forming device which will receive wires of desired lengths, and completely form a strong and 10 serviceable garment hanger.

A further object of my invention is to provide a device of the type described which will receive and operate upon a plurality of wires at one time.

15 A further object of my invention is to provide a device of the type described which will completely form a hanger with great rapidity.

20 A further object of my invention is to provide a device of the type described which is durable and efficient for the purpose intended.

25 Other objects and advantages will appear in the following specification, and the novel features of the invention will be particularly pointed out in the appended claims.

My invention is illustrated in the accompanying drawings, forming part of this application, in which—

30 Figure 1 is a plan view of the device, portions thereof being left out for clarity,

Figure 2 is a diagrammatic view of the device,

35 Figure 3 is a section along the line 3—3 of Figure 1,

Figure 4 is a section along the line 4—4 of Figure 1,

Figure 5 is a section along the line 5—5 of Figure 4,

40 Figure 6 is a section along the line 6—6 of Figure 1,

Figure 7 is a section along the line 7—7 of Figure 1,

45 Figure 8 is similar to Figure 7, the mechanism shown in a different position,

Figure 9 is a front elevation of the device, portions thereof being left out for clarity, and

50 Figure 10 is a section along the line 10—10 of Figure 1.

In carrying out my invention, I provide a supporting frame 1 carrying a main or power shaft M, see Figure 2. A shaft A is operatively connected to the main shaft 55 M by a chain 2. A sprocket 3 is rigidly mounted upon the forward end of the shaft

A. A shaft B is operatively connected to the shaft A by a chain 4 which is placed upon the sprocket 3 and a sprocket 5, the latter being rigidly mounted upon the shaft 60 B. A shaft X is operatively connected to the shaft A by a chain 6, and a shaft Y is operatively connected to the shaft B by a chain 7.

The frame 1 supports a wire container 8 65 which is adapted to receive wires 9. Discs 10 having a plurality of recesses 11 therein are mounted upon a shaft 12, which is carried by the frame 1. Guides 13 are secured to the wire container 8 and extend a short 70 distance around the discs 10. A rotation of the discs 10 in the direction of the arrow 14 will cause the wires 9 to drop one at a time into the recesses 11 and be carried downwardly until they are released by the 75 guides 13. The discs 10 are operatively connected to the shaft B by means of gears 15, 16 and 17, mounted upon shafts 12, 18 and 19, respectively, sprockets 20 and 21 mounted upon shafts 19 and 22, respectively, 80 and connected by a chain 23; and bevel gears 24 and 25 mounted upon shafts 24 and B, respectively. The operation of the shaft B is shown in Figure 2, and has been explained in the previous paragraph. 85

As the wires 9 drop from the discs 10, they fall upon finger bars 26 and 27 and are moved forwardly. The mechanism for moving the finger bars 26 and 27 is shown in Figures 4 and 5. The finger bars 26 90 and 27 each have a recess 28 therein. A bar 29, which is adapted to be received in the recesses 28, is rigidly mounted upon rods 30. The rods 30 are slidably disposed in bearing plates 31 and 32. Arms 33 are 95 pivotally mounted at their upper ends to the rods 30, and at their lower ends to levers 34. The free ends of the levers 34 are rigidly connected, one to each end of a shaft 35 which carries an arm 36. The arm 36 is operatively connected to an eccentric 37 by lever 38. The eccentric 37 is operatively connected to the shaft B, and the shaft B is operatively connected to the power shaft M, as shown in Figure 2. 100

When one of the wires 9 drops upon the finger bars 26 and 27, the fingers 39 move the wire forward beneath the spring-pressed gripping plates 40 to the position F where the first operation upon the wire takes place. 110 The mechanism used in the first operation is shown in Figure 6. The wire 9 upon reach-

ing the position F is first firmly gripped, and then the end 41 is formed into a hook. The means for gripping the wire 9 consists of a plate 42 rigidly mounted at one end to the supporting frame 1. I have removably secured a die 43 to the plate 42. The die has flat lower and upper surfaces 44, and the ends thereof are provided with projections 45.

10 A plate 46 carrying an integral lug 47 is pivotally mounted at one end to the frame 1. At the free end of the movable plate 46, I have pivotally mounted an adjustable bar 47'. Extending between the free end of 15 the bar 47' and the frame 1 and pivotally secured to both is a rod 48, carrying a roller 49. The roller 49 is positioned above the shaft Y and rides upon a cam disc 50 which is mounted upon the shaft Y. The cam disc 20 50 has a high portion 51 and a low portion 52. To the shaft Y, I have also mounted an eccentric 53 which is operatively connected to a forming die 54 by a lever 55. The forming die 54 is pivotally mounted upon the 25 movable plate 46.

When the first operation is completed, the wire 9 is released and moved forward by fingers 56 on the finger bars 26 and 27 to the position S shown in Figure 1. At 30 this position, the wire 9 is again gripped and the second operation takes place. The mechanism used in the second operation is shown in Figures 7 and 8. Figure 7 shows the mechanism just before the operation 35 takes place, and Figure 8 shows the mechanism as the operation is about finished. A plate 57, carrying a bending die 58 and a forming die 59, is rigidly mounted upon the frame 1. A movable plate 60 is positioned below the plate 57 and is pivotally mounted upon the frame 1. The movable plate 60 is provided with an integral lug 61 having an inclined surface 62. The free end of the movable plate 60 is operatively 40 connected to one end of the bar 63 by means of a link 64. The free end of the bar 63 is pivoted to the frame. A cam disc 65 is rigidly mounted upon the shaft X and is in contact with a roller 66 which is mounted 45 upon the bar 63. The cam disc 65 has a high portion 67 and a low portion 68.

The shaft X also carries a cam 69 which is in engagement with a roller 70. The roller 70 is rotatably mounted at one end 50 of a lever 71 which is pivotally mounted near its center to the frame 1 and at its free end to a rod 72. A rod 73, connected at one end to the rod 72 and at the opposite end to a stationary bar 74, is pivotally connected near its center to the bending die 58. The bending die 58 is guided in its movement by tongued blocks 75 which project into the slots 76 in the walls of the die. The bending die 58 is normally held upwardly by a spring 71'.

In front of the cam disc 65 and upon the shaft X is mounted an eccentric 76 which is operatively connected to the forming die 59 by means of a link 77. As the eccentric 76 is moved downwardly, the forming die 59 is drawn downwardly about its pivot 78 until the center pin 79 is in alignment with the center of a forming block 80. Then by a further movement, a roller 81 upon the forming die 59 will roll for a short distance around the block 80.

Upon the completion of the second operation, the wire 9 is released, caught by tongue 82, and moved forwardly to the position T, as shown in Figures 1 and 9. The wire 9 is then gripped between a forming die 83 and a movable plate 84. One end of the plate 84 is pivoted at 85 to the frame 1, and the other end, having an elongated slot 85' therein, is movably held by a bolt 86. A bar 87 is pivotally connected at one end to the plate 84 and carries a roller 88 at the other end. The bar 87 is held against sideward movement by a rod 89. A cam 90 is fixed to the shaft B, and is in registration with the roller 88. The cam 90 has a high portion and a low portion. When the high portion strikes the roller 88, the plate 84 is raised, forcing the wire 9 against the bottom 91 of the forming die 83.

The movable plate 83 is provided with arms 92 and 92' which are pivotally mounted thereupon. Eccentrics 93 and 93' are fixed to the shafts A and B, respectively. Bars 94^a and 94^b operatively connect the arms 92 and 92' to the eccentrics 93 and 93', respectively. The eccentric 93 will rotate at the same speed that the eccentric 93' is rotated, thus simultaneously raising and lowering the arms 92 and 92'. As the arms are raised, the integral flanges 94 and 94' catch the free ends of the wire 9 and force them upwardly. The head portion 95 of the wire 9 passes between the spring-pressed guide 96 and is forced into the dotted line position shown in Figure 9. As the other end of the wire is brought upwardly, it is forced away from the frame 1 by cammed blocks 97 and 98. The hooked portion 42 is forced beyond the neck 99 and becomes hooked thereon when the wire is released. A spring-actuated lever 100 is a positive means for returning the ends of the wire 9 into hooked position, if the tension of the wire should not do so.

As the arms 92 and 92' are being returned to their lower position, a cam 101, which is carried by the shaft A, strikes a roller 102 and forces it upwardly. The roller 102 is operatively connected to a plunger 103, and the plunger is forced upwardly, taking with it a vertical die 104. The vertical die 104 is held in this position until a horizontal die 105 is forced outwardly by a cam 106, see Figure 1, thus pressing the hook portion 105 of the wire 9 into the vertical die 104.

42 about the neck 99. The garment hanger is now completed. By further movement of the mechanism, the plate 84 releases the hanger, the fingers 107 on the finger bars 27 5 catch the lower portion of the hanger and force it free from the device as a cam 108 strikes a plunger 109 and forces the upper portion of the hanger free from the device.

From the foregoing description of the 10 various parts of the device, the operation thereof may be readily understood. The wires 9 are fed into the container 8, taken one at a time, and dropped upon the finger bars 26 and 27. As the finger bars move 15 forwardly, the fingers 39 catch the wire and move it into the position F. At this position, the wire is gripped between the lug 47 and the die 43. The forming die 54 is then actuated, thus forcing the end 42 of the 20 wire 9 upwardly about the projection 45, and into the shape of a hook.

As the first wire is being released from the first operation, the finger plates 26 and 27 move backwardly, receive a second wire, 25 and as the finger bars are again moved forwardly, the fingers 56 carry the first wire to the position S as the fingers 39 carry the second wire to the position F. As the second wire is having the first operation, the 30 first wire is having the second operation. It will be observed that the quick movement of the first wire from the position F to the position S will cause the wire to turn so that the hook portion 42 will extend toward 35 the rear of the device. In the second operation, the wire is first gripped between the movable plate 60 and the stationary plate 57. The bending die 58 is then moved downwardly forcing a portion of the wire 9 against the inclined surface 62. The forming die 59 is then actuated, thus forcing the 40 end of the wire 9 about the block 80.

When the dies 58 and 59 return to their 45 normal position and the first wire is released from the second operation, the second wire is released from the first operation and the finger bars 26 and 27 have moved to the rear of the device for a third wire. As the fingers 39 move the third wire to the position F, the fingers 56 move the second wire to the position S and the fingers 82 move the first wire to the position T. As the 50 third wire is having its first operation, and the second wire is having its second operation, the first wire is having its third operation. The center portion of the first wire is rigidly held between the movable plate 84 and the bottom 91 of the die 83. The 55 flanges 94 and 94' on the arms 92 and 92' engage with the free ends of the wire, and force them to conform to the die 83. The hook portion 42 catches against the neck 99 and is firmly clamped in place by the vertical die 104 and the horizontal die 105.

Upon the completion of the third oper-

ation, the finger bars return to the rear of the device for a fourth wire. The first, second, and third wires are released at this time. As the fourth wire is caught by the fingers 39 and brought forwardly to the position F, the third wire is caught by the fingers 56 and brought forwardly to the position S, the second wire is caught by the fingers 82 and brought forwardly to the position T, and the first wire is engaged at its 70 bottom portion by the fingers 107, and at the top by the plunger 109, and freed from the device.

It will be observed that the feeding mechanism, the mechanism used in the first, second, and third operations, and the mechanism for operating the finger bars 26 and 27, are all operatively connected to the main or power shaft M.

I claim:

1. A device of the type described comprising a frame, means for feeding wires, means for forming a hook in one end of each wire, means for conveying the wires from the feeding means to the hook-forming 90 means, means for fashioning a head in the other end of the wires, means for bending the wires for causing the hook-shaped ends of each wire to engage with its opposite end adjacent to the head, and means for binding the 95 hook of each wire in place.

2. A device of the type described comprising a frame, means for feeding wires, means for forming a hook in one end of each wire, means for fashioning a head in 100 the other end of the wires, means for bending the wires for causing the hook-shaped ends of each wire to engage with its opposite end adjacent to the head, means for binding the hook of each wire in place, and means 105 for conveying the wires from said feeding means to the hook-forming means, said head-fashioning means, and said bending means.

3. A device of the type described comprising a frame, means for feeding wires, 110 means for forming a hook in one end of each wire, means for fashioning a head in the other end of the wires, means for bending the wires for causing the hook-shaped ends of each wire to engage with its opposite end adjacent to the head, means for binding the hook of each wire in place, means for conveying the wires from said feeding means to the hook-forming means, said head-fashioning means and said bending means, and means 115 cooperating with said last named means for freeing the wires from the device.

4. In a device of the type described, wire-gripping means, means for automatically moving a wire into engagement with said first named means, and means for forming a hook in the wire, said wire-moving means automatically removing the wire when it is released from said gripping means.

5. In a device of the type described, wire- 120

- gripping means, means for automatically moving a wire into engagement with said gripping means, means for forming a hook in one end of the wire, a second wire-gripping means, said wire-moving means removing the wire from said first named gripping means and into engagement with said second named gripping means, and means for fashioning a head in the other end of said wire.
6. In a device of the type described, means for forming a hook in one end of a wire, means for fashioning a head in the other end of said wire, wire-gripping means, means for conveying the wire from said hook-forming means to said head-fashioning means, and from said head-fashioning means to said wire-gripping means, and means for bending the ends of said wire upwardly and inwardly, causing the hook-shaped end to engage with its opposite end adjacent the head.
7. In a device of the type described, means for forming a hook in one end of a wire, means for fashioning a head in the other end of said wire, wire-gripping means,
- means for conveying the wire from said hook-forming means to said head-fashioning means, and from said head-fashioning means to said wire-gripping means, means for bending the ends of said wire upwardly and inwardly, causing the hook-shaped end to engage with its opposite end adjacent the head, and means for rigidly binding the hook of the wire in place.
8. In a device of the type described, means for forming a hook in one end of a wire, means for fashioning a head in the other end of said wire, wire-gripping means, means for conveying the wire from said hook-forming means to said head-fashioning means, and from said head-fashioning means to said wire-gripping means, means for bending the ends of said wire upwardly and inwardly, causing the hook-shaped end to engage with its opposite end adjacent the head, means for rigidly binding the hook of the wire in place, and means cooperating with said conveying means for discharging the hanger when completed.

RAYMOND KNABLE.
